[57] ABSTRACT

An electric switch having an elongate housing with a base plate on one side and a strip key on an opposite side, the key being connected to an operating element. When the key is moved towards the base plate the operating element is moved along the axis of the housing to operate a button switch.

ELECTRIC SWITCH

BACKGROUND OF THE INVENTION

1. Field of the Invention

This invention relates to an electric switch.

2. Description of the Prior Art

The known electric switches of small dimensions operable by press knobs or rockers are not easy to find with the hand in darkness, which is noticeable in a disadvantageous manner especially in the case of bedside lamps. Likewise the switch operation must be effected with the finger tips, which is possible only if at least one hand is free.

SUMMARY OF THE INVENTION

It is the object of the present invention to eliminate this disadvantage in a manner in which the press key has an extra-ordinarily large key area which permits the force-engaging transmission of the operating movement to the electric press switch element, at any point in the region of its length.

For this purpose according to this invention in a housing of bar form there is arranged an upwardly and downwardly movable key of strip form which protrudes partially from the housing and extends approximately over the length of the housing, and in working connection with the key there is an operating element movable in relation to the key and acting upon a press switch, all in such a way that on depression of the key the operating element can be displaced along the key and the press switch can be operated.

For wall lamps a flange-like securing plate can be secured to the switch housing for mounting on the wall. In the case of bedside and table lamps a switch housing of bar form with a secure standing surface for placing on a table top or other support is sufficient.

BRIEF DESCRIPTION OF THE DRAWING

An example of a form of embodiment of the object of the invention is illustrated in the drawing, wherein:

FIG. 1 shows a vertical partial longitudinal section through the switch in the basic position;

FIG. 2 shows a partial longitudinal section through the switch with the key depressed;

FIG. 3 shows a horizontal partial longitudinal section along the line III-III in FIG. 2;

FIG. 4 shows a cross-section through the switch along the line IV-IV in FIG. 2;

FIG. 5 shows a plan view of the switch on a smaller scale; and

FIG. 6 shows a lateral view of the switch.

DESCRIPTION OF THE PREFERRED EMBODIMENT

The switch constructed according to FIGS. 1 to 4 for placing on a table has a housing 1 of bar form which is closed off on its under side by a bottom plate 2 serving as standing surface. This plate is secured by means of screws 3 to counter-sunk corner projections 4 of the housing. The cover of the housing 1 is provided with a longitudinal slot 5 in which a press key 6 of strip form is guided. On the bottom plate 2 there are seated two vertical longitudinal bearing pieces 7, 7' which serve as sliding guide for the press key 6. The longitudinal bearing pieces 7, 7', in the region of bearing projections 8, 8', protruding laterally from them, are pierced each by

a horizontal spindle 9 and 9' respectively which extend transversely of the key 6. On each of these spindles there is rotatably mounted a rotating member 10, 10' respectively acting as bell-crank lever. The lever arm 11, which swings about the horizontal middle position of each of the two rotating members 10 and 10' is articulatedly connected by spindle journals 12 with the press key 6, and the lever arm 13, which swings about the vertical middle position, of each of the two rotating members 10, 10' is articulatedly connected by joint journals 14 with an operating rod 15 extending in the longitudinal direction of the housing 1, which rod is guided between the bearing pieces 7, 7' and the rotating members 10, 10'. The foot-shaped end 15' of the operating rod 15 is cranked off towards the axis of the contact button 16 of a conventional press switch 17 which is clamped in between the prongs of a retaining fork 18 seated on the bottom plate 2 of the housing 1. Two cutaway portions 19, 19' of the press key 6 permit unhindered movement of the latter in relation to the projections 8, 8' and the spindle journals 14 which protrude slightly into the cutaway portions.

By pressing in of the key 6 in the direction of the arrow *a* in FIG. 1, the rotating members 10, 10' are rotated in the counterclockwise direction into the position according to FIG. 2 and thus the operating rod 15 is moved in the direction of the arrow *b* in FIG. 1. By this movement of the operating rod 15 the contact button 16 of the conventional button switch 17 is operated against the action of the spring installed in this switch. By release of the press key 6 the operating rod 15 is brought into the initial position by the spring action of the contact button 16 and at the same time by pivoting of the rotating members 10, 10' the press key 6 is raised into its basic position according to FIG. 1.

When the switch is used for wall lamps its housing 1 is provided with a securing plate 20 screwed fast to the housing bottom plate 2, which plate facilitates the securing of the switch on a wall by means of screws. When the switch is secured to a wall, operation of the press key 6 is possible with the upper body, for example with the shoulder or the upper arm, so that switching operations can be effected by a person whose hands are not free. It is essential that the press key 6 is operable over the whole range of its length without a directed operating movement.

The switch as described is of course suitable also for pedal operation, especially where the immediate finding of small switch knobs is difficult.

Whether the press key 6 is depressed at the one or the other end, the correct switching operation is ensured by virtue of its vertical guidance and the cooperation of the rotating members 10, 10' and the operating rod 15. It is important that an ordinary commercial press button switch 17 can be used, which has a favourable effect upon the purchase costs of the object of the invention, for the essential parts 6, 10, 10' and 15 are relatively simple to produce and assembly of the whole can be carried out easily and quickly.

I claim:

1. An electric switch comprising:

- a. a housing having a bar form with stationary supports extending inwardly,
- b. a press key having a strip form which protrudes partially from the housing and is mounted for upward and downward movement within the housing,

- c. said key extending approximately over the length of the housing,
  - d. a press switch mounted in the housing,
  - e. an operating rod being displaceable beside and extending in the longitudinal direction of the press key, and
  - f. at least two rotatable members having spindles and acting as bell-crank levers being mounted on the stationary supports and articulatedly connected to the operating rod,
  - g. said key being effective to rotate said rotatable members for displacing the operating rod in a longitudinal direction thereby operating the press switch,
  - h. said stationary supports having laterally protruding bearing projections for supporting said spindles,
  - i. said key having cutaway portions which bridge over the laterally protruding bearing projections.
2. An electric switch comprising:
- a. a housing having a bar form with support projections extending inwardly,
  - b. a press key having a strip form for upward and downward movement within the housing,
  - c. said press key extending approximately over the length of the housing,
  - d. a press switch mounted in the housing, and
  - e. an operating element movable connected to the key by articulation journals to operate the press switch when the press key is depressed downwardly in said housing,
  - f. said press key having cutaway portions into which the support projections and articulation journals partially protrude.
3. An electric switch comprising:
- a. a housing having a bar form with stationary supports extending inwardly,
  - b. a press key having a strip form which protrudes partially from the housing and is mounted for upward and downward movement within the housing,
  - c. said key extending approximately over the length of the housing,
  - d. a press switch mounted in the housing,
  - e. an operating rod being disposed beside the key for displaceable movement along the longitudinal axis of the rod, and
  - f. at least two rotatable members acting as bell-crank levers being mounted on the stationary supports,
  - g. each rotatable member carries two spindle journals

50

- that are parallel with respect to the axis of rotation of the rotating member,
- h. each rotating member including a first lever arm articulatedly connected by one of the spindle journals to the press key for swinging about a horizontal middle position and a second lever arm articulatedly connected to the operating rod for swinging about a vertical middle position.

4. An electric switch comprising:

- a. a housing having a bar form,
- b. a press key having a strip form which protrudes partially from the housing and is mounted for upward and downward movement within the housing,

c. said key extending approximately over the length of the housing,

d. a press switch mounted in the housing,

e. an operating rod being disposed beside the press key for displaceable movement along the longitudinal axis of the rod, and

f. rotatable members acting as bell-crank levers mounted in the housing to convert the movement of the press key into a movement direction of the operating rod transverse thereto.

5. An electric switch comprising:

a. a partially exposed press key means mounted for upward and downward movement within a housing,

b. a press switch mounted within the housing,

c. a switch operating means displaceably mounted within the housing to operate the press switch, and

d. connecting means for connecting the press key means to the switch operating means and being effective to displace the switch operating means when the press key means is moved upwardly and downwardly.

6. An electric switch as defined in claim 5 wherein the switch operating means includes an operating rod and

the connecting means includes a rotatable member that is connected at one location to the operating rod and at another location to the press key means.

7. An electric switch as defined in claim 5 wherein the press key means includes an elongated strip form element extending along the length of the housing.
